said Davis

Filed Dec. 24, 1962, Ser. No. 246,727
9 Claims. (Cl. 214—138)

This invention relates to an improved construction for self-propelled excavators or mechanical shovels.

In self-propelled excavators of conventional construction the boom supporting body and the boom either swing together as a unit about a fixed vertical body axis, or the boom assembly swings about a fixed vertical axis at one end of the body while the body remains stationary. In either case it is impossible to position the excavator so that the bucket at the outer end of the boom can excavate a trench immediately adjacent to and alongside a building wall with the boom moving up and down in a plane parallel to the building wall.

With excavators of conventional construction it is also well nigh impossible to dig a trench or other excavation having a vertical wall which runs transverse to and immediately adjacent the ground on which the excavator is resting.

It is a primary object of this invention to obviate these disadvantages by providing an excavator which has independent vertical pivot axes for both the body and the boom assembly, thus making it possible for the operator to first pivot the body so that the boom pivot axis is moved to a position immediately adjacent a building wall, and to thereafter swing the boom about its own vertical pivot axis to dump material removed from the trench or excavation into a nearby truck without the necessity of pivoting the boom supporting body during each bucket dumping operation.

An additional object is to provide a mechanical shovel which includes, in addition to the above mentioned construction features, a horizontal tilt axis between the body and its supporting mobile chassis, which makes it possible to level the body when its transporting chassis is located on a hillside, which in turn makes it possible to dig a trench vertically into the ground alongside a building wall, even though the ground slopes upward or downward away from the building wall.

The above and other objects will be better understood when the following description is read in connection with the accompanying drawings, in which:

FIG. 1 is a perspective view of a self-propelled excavator embodying the invention;

FIG. 2 is an exploded view, in perspective, showing details of construction of the excavator illustrated in FIG. 1;

FIGS. 3 and 4 are top plan schematic views illustrating typical operations of which an excavator embodying the invention is capable; and

FIG. 5 is a front elevational view schematically illustrating the excavator performing another type of operation.

Generally, an excavator embodying the invention includes a power driven mobile ground supported chassis which includes a weight supporting frame; an intermediate frame mounted on the chassis for lateral tilting movement with respect thereto about a central fore and aft horizontal axis; a body mounted on the intermediate frame for swinging movement about an axis normal to the plane of the intermediate frame; a work performing assembly including an elongated bucket carrying boom mounted on one end of the body for swinging movement about an axis parallel to the body swinging axis, and also for movement about a transverse axis normal to the body swinging axis; a power unit carried by the body; means

2

for transmitting power from the power unit to the mobile chassis for propelling the chassis regardless of the relative positions of the body, the body supporting intermediate frame, and the chassis frame; power unit operated means for tilting the intermediate frame about its axis; power unit operated means for swinging the body about its upright axis; and power unit operated means for moving the boom about both its axes.

Details of construction

10 Referring particularly to FIG. 2 of the drawings, the chassis of the excavator illustrated is designated as a whole by the numeral 11, the body supporting intermediate frame is designated as a whole by the numeral 16, the body is designated as a whole by the numeral 15, and the boom assembly is designated as a whole by the numeral 18.

15 The mobile chassis includes conventional endless tracks 12 which are driven independently through a transmission 14, which in turn is driven by a hydraulic motor 13 mounted on the transmission housing. The chassis frame includes fore and aft spaced parallel transverse frame members 20 and 21 which rigidly carry fore and aft aligned pivot pin bearings 22.

20 The intermediate frame 16 includes transversely spaced parallel frame members 25 and transversely disposed parallel channel cross section frame members 26 and 27, rigidly connected to the frame members 25. The transversely disposed frame members 26 and 27 are fitted with 25 central fore and aft aligned bearings 29 which cooperate with the bearings 22 on the chassis frame, and with separate pivot pins, to mount the intermediate frame on the chassis frame for tilting movement about the axis 22. The intermediate frame carries a body pivot pin 35 which 30 is rigidly mounted in upright position on the cross frame member 27.

35 In addition, the intermediate frame 16 includes a transverse arcuate channel section track 39 which is welded or otherwise rigidly secured to the forward ends of the frame members 25, and three rollers 36 rotatably mounted on spaced brackets 37, one on frame member 26, and the other two at the respective aft ends of the frame members 25. The purpose of the track 39 and the rollers 36 will be explained in connection with the body section 15.

40 The elongated body 15 is generally oval shaped in plan form, as clearly shown in FIGS. 3 and 4. It includes spaced parallel side frame members 48, a rigid transverse cross frame member at its forward end connected to the forward ends of the frame members 48, but not shown in FIG. 2. It also includes rear channel section cross frame members 49 and 51, which are likewise rigidly secured to the aft ends of the frame members 48.

45 Intermediate its ends the body frame rigidly supports a heavy transverse plate 50 which has a central hole 52 for receiving the pin 35 on the intermediate frame.

50 Concentrically surrounding the hole 52 the body frame rigidly carries three arcuate track members 53, 54 and 55 which in effect constitute a three-quarter circular turn table guide for the body, since all three of these members lie in the same transverse plane. They are of channel section to receive the rollers 36 on the intermediate frame 16.

55 Additionally, at its forward end, the body rigidly carries a bracket 57, which in turn carries transversely spaced rollers 58 which are received in and roll on one flange of the channel in track member 39 when the body is mounted in its normal position on the pivot pin 35. The rollers 58 in the arcuate channel member 39, and the central roller 36 which rolls in the channel of track member 53 serve to stabilize the body on the intermediate frame 16 and prevent its fore and aft tilting with respect to the intermediate frame. The two rollers 36 at the op-

posite sides of the intermediate frame, seated in the track members 54 and 55 on the body serve to stabilize the lateral tilting movement of the body with respect to the intermediate frame. Thus when the body 15 is mounted on the intermediate frame by means of the pivot pin 35 and the rollers 36 and 58, and the intermediate frame is mounted on the chassis frame 11 by means of pivot pins passing through the bearings 22 and 29 on the intermediate frame and on the chassis frame, the intermediate frame is capable of tilting laterally with respect to the chassis frame, and during such tilting movement in either direction, the body tilts with the intermediate frame. Also, when the three mentioned sub-assemblies are assembled together, as in FIG. 1, the body is capable of swinging movement about the axis 35, which is normal to the plane of the intermediate frame, and normal to the tilting axis 22.

The power unit operated means for tilting and stabilizing the intermediate frame with relation to the chassis is illustrated in the form of a pair of double acting hydraulic working cylinders 32 and 33. These cylinders have one end pivotally connected to the chassis frame cross member 21, as shown, and their opposite ends are pivotally connected to the respective opposite ends of the intermediate frame cross member 27. A conventional hydraulic valve, not shown, is used to extend the length of one of these cylinders while the other cylinder is simultaneously reduced in length, and vice versa.

As a means of swinging the body about its vertical axis 35, the invention includes a pair of spaced hydraulic cylinders 59, each having an end pivotally connected to a respective aft end of the intermediate frame members 25, and their opposite ends pivotally connected to the body at transversely spaced points in the channel section cross member 51. Similarly, a suitable conventional hydraulic valve, not shown, is provided for extending the length of one of the cylinders 59 while the length of the other is reduced, and vice versa.

The boom 64 has one end pivotally connected to a supporting bracket 75 at 68, the pivot pin 68 lying in a transverse plane normal to the body pivot axis 35. The bracket 75 is also pivotally mounted on an upright king pin 70 which is supported at its upper and lower ends by the forward end of the body. Thus the boom is capable of swinging in a plane parallel to the body frame on an axis 70 which is parallel to the body pivot axis 35, and is also capable of being moved up and down about the pivot pin 68, which is normal to the axis 70. A conventional rotary hydraulic working cylinder housed in the body housing 66 and connected to the king pin 70 serves to swing the bracket 75 from side to side, thereby similarly swinging the boom 18.

The entire boom and bucket assembly is shown in FIG. 1. A bucket carrying arm 63 has one end pivotally mounted on a transverse pivot axis 44 at the outer end of the boom 64. The other end of arm 63 is pivotally connected at 76 to a conventional digging bucket or shovel 62.

Boom 64 is moved about its transverse axis 68 by means of a double acting working cylinder 65, while the arm 63 is moved about its transverse pivot axis 44 by means of a double acting working cylinder 77. Similarly bucket 62 is moved about its transverse pivot axis 76 by means of a double acting working cylinder 78. The boom assembly is conventional and further description of structural details is considered unnecessary.

Body 15 supports an engine housing designated generally by the numerals 42 and 43, which houses a power unit 46. The power plant 46 drives a hydraulic pump (not shown), and the necessary conduits are provided between conventional valves and the pump, and between the valves and the individual power units on the excavator, including the hydraulic motor 13 for driving the tracks 12, the cylinders 32 and 33 for tilting the transverse frame, the cylinders 59 for swinging the body with relation to the

transverse frame, and the boom and bucket assembly operating cylinders 65, 77 and 78.

Operation

FIGS. 3, 4 and 5 of the drawings illustrate several of the difficult operations of which the described excavator is capable. In each of these figures the letter W represents a building wall.

In FIG. 3 the excavator has been positioned with its chassis alongside and parallel to the building wall. The body 15 has been swung clockwise until the pivot point 70 is positioned on the center line of a trench 79 to be dug alongside the building wall. Thereafter it is only necessary to actuate the boom and bucket assembly to dig the trench, lift the material from the trench in the bucket, and swing the boom counterclockwise to dump the material into a nearby truck. This can be done while the body 15 remains stationary.

In the operation shown in FIG. 4 an excavation is being made with a vertical wall 80 running transverse to the chassis 11 and immediately adjacent the forward end of the chassis. In this case the body 15 is swung counterclockwise until the boom swing axis 70 is in a position to permit boom assembly 18 to operate parallel to the wall to be dug. Thereafter the boom assembly can be actuated to dig the excavation, to lift material from the excavation, and to dump it into a nearby truck, as shown, without the necessity of intermittently swinging the body 15 about its pivot axis.

In FIG. 5 the operation illustrated in FIG. 1 is being performed, but the ground on which the chassis sets is sloping downward away from the building wall. In this case it is only necessary to level the body 15 by tilting the intermediate frame 16 about its fore and aft pivot axis 22.

Having described the invention with sufficient clarity to enable those familiar with this art to construct and use it, we claim:

1. An excavator comprising:
a self-propelled ground supported chassis including a rigid weight supporting frame;
an intermediate body supporting frame;
means pivotally mounting said intermediate frame on said chassis for lateral tilting movement with respect thereto about a central fore and aft horizontal axis;
a body;
means pivotally mounting the body on said intermediate frame for swinging movement about an axis normal to the pivot axis of the intermediate frame; and
a work performing assembly including an elongated boom mounted on one end of the body for independent swinging movement about an axis spaced from and parallel to the body swinging axis.
2. The excavator described in claim 1, and
cooperating means on said body and on said intermediate frame for stabilizing the body with respect to the frame during body swinging movement.
3. The excavator described in claim 1, and
power unit operated means for tilting said intermediate frame about its axis;
power unit operated means for swinging the body about its axis; and
power unit operated means for swinging said boom about its axis.
4. The excavator described in claim 1, and
power actuated means connected to the intermediate frame and to the chassis frame for maintaining the intermediate frame in a selected position with respect to the chassis, and for laterally tilting the intermediate frame with respect to the chassis.
5. The excavator described in claim 1, and
power actuated means connected to the intermediate frame and to the body for maintaining the body in a selected position with respect to the intermediate frame, and for swinging the body in either direction about its pivot axis.

6. The excavator described in claim 1 in which the said boom is also mounted on the body for up and down movement about a transverse axis which is normal to its swinging axis.

7. The excavator described in claim 1, and
a power unit mounted on the body; and
means independent of the tilting axis of the intermediate frame and of the body swinging axis for transmitting power from the power unit to the mobile chassis for propelling the chassis regardless of the 10 relative positions of the body, the body supporting intermediate frame, and the chassis frame.

8. The excavator described in claim 1 in which that end of the body on which the work performing assembly is mounted is symmetrically tapered outwardly in plan 15 form.

9. The excavator described in claim 1 in which both ends of the body are symmetrically tapered outwardly in plan form.
